HEEL SUPPORT FOR A SKI BINDING

Reinhold Vöster, Jahnstrasse 31, Stuttgart-Degerloch, Germany, and Eugen Schnell, Walter-Helmes-Weg 32, Leonberg, Germany

Filed Nov. 14, 1966, Ser. No. 4,642

Claims priority, application Germany May 13, 1966

Term of patent 14 years

(Cl. D34—14)

FIG.1

FIG.2

FIG.3

FIG.4

FIG.5

FIG.6

FIGURE 1 is a perspective view of the heel support for a ski binding embodying our new design, viewing the heel support from the left side thereof;

FIGURE 2 is a top plan view thereof;

FIGURE 3 is a right side elevational view thereof;

FIGURE 4 is a front elevational view thereof;

FIGURE 5 is a rear elevational view thereof;

FIGURE 6 is a bottom plan view thereof.

We claim:

The ornamental design for a heel support for a ski binding, as shown.
